UNITED STATES PATENT OFFICE.

THOMAS E. SHANNON, OF CHICAGO, ILLINOIS, ASSIGNOR TO KEENO KEYLESS LOCK COMPANY, OF CHICAGO, ILLINOIS, A CORPORATION OF ILLINOIS.

DOOR LOCK.

Application filed July 19, 1919. Serial No. 312,058.

To all whom it may concern:

Be it known that I, THOMAS E. SHANNON, a citizen of the United States, residing at Chicago, in the county of Cook and State of

5 Illinois, have invented certain new and useful Improvements in Door Locks, of which the following is a specification.

This invention relates to improvements in door locks and has for its object to provide 10 an improved door lock which may be unlocked from the outside by means of a combination mechanism used in conjunction with the lock bolt member.

Another object consists in the provision 15 of means to lock the combination mechanism in position, permitting opening of the door from either the inside or outside, as desired. Still another object consists in providing means to lock the combination mechanism in position to prevent unlocking of the 20 door from the outside even when in possession of the combination.

Another object consists in the provision 25 of mechanism which will permit attachment of my improved lock on either side of a door and upon a door which may open in either direction.

Still another object consists in the provision 30 of a lock mechanism of the character described in which unlocking latch members may be used or rotatable knob members, as desired.

Still another object consists in the construction 35 of the lock casing so that the purchaser of a complete mechanism, ignorant of the combination will be able to ascertain the combination without taking the case apart.

These and other objects will be more fully 40 set forth and described in the following specification and shown in the accompanying drawings in which—

Figure 1 is a side elevation of a door plate utilizing my invention;

45 Fig. 2 is an end elevation of a door having my improved mechanism applied thereto;

Fig. 3 is a vertical section along the line 3—3 of Figs. 1 and 4 drawn to an enlarged 50 scale;

Fig. 4 is a vertical section along the line 4—4 of Fig. 2;

Fig. 5 is a horizontal sectional view along the line 5—5 of Fig. 4;

Fig. 6 is a horizontal sectional view along 55 the line 6—6 of Fig. 4;

Fig. 7 is a sectional detail of the structure shown in the lower portion of Fig. 3, showing rotatable knobs and rocker arms substituted for the latch members shown in Fig. 3; 60

Fig. 8 is a detail of the mechanism shown in Fig. 7;

Fig. 9 is a front elevation of the interior 65 of a portion of the lock casing showing the slide bar in position;

Fig. 10 is a similar view of the inner face 70 of the cover of the casing showing the auxiliary slide bar in position;

Fig. 11 is a front elevation of the exterior 75 of a portion of the case covering;

Fig. 12 is a detailed elevation of the push bar mechanism; and

Figs. 13, 14, and 15 are perspectives of the 75 combination disks, the eccentricity being exaggerated for the purpose of illustration.

Like numerals refer to like elements throughout the drawings, in which 10 designates generally a door in which is mortised or inset a lock casing 11 having the face plate 12 and cover 12^a.

A bolt 13 of conventional form is provided having the usual bevelled side to permit forcing back by co-action with the striker plate, not shown, which is carried by the door jamb. This bolt is carried by a reciprocable bar 13^a 80

which is provided with notches or recesses 13^b at top and bottom of its rearward extremity, such extremity being slightly enlarged. The body of the bolt bar 13^a is guided by and reciprocates between stationary posts 14 carried by the lock casing. Engaging the lowermost of the recesses 13^b is a bell crank 15 having the engaging tip or extremity 15^a fitting in the notch 13^b, as shown in Fig. 4. A lower angularly disposed tip 15^b projects laterally of the bell crank 15 and is engaged by a leaf spring 16 slightly bent at its other extremity at 16^a and fitting between a pair of studs 17, this arrangement bringing resistance to bear 90

against the movement of the crank 15 which is pivoted on the stud 18, as shown in Fig. 4. Reciprocably mounted in the casing is the slide bar 20 (see Fig. 3 for example) having

100

a projecting lug 20^a adjacent its lower extremity, this lug being normally in contact with the arm 15^b of the crank 15. At the lower end of the slide bar 20 is the contact 5 face 20^b adapted to be engaged by an operating member, as will be more fully described hereinafter. Superimposed upon the slide bar 20 is an auxiliary slide bar 21 having a slot 21^a in which slides the lug 20^a. The 10 auxiliary slide bar overlies the bolt bar 13^a, as shown in Fig. 4, and is provided at its extremity 21^b with the reduced laterally projecting stud or lug 21^c (see Figs. 3 and 4), this lug or stud being intended to coact with 15 the disc members of the combination mechanism, as will be described hereinafter.

When arranged as shown in the drawings, the slide bar 20 lies between and is guided in its reciprocal movement by the upper pair 20 of lugs 19^a and 19^b and the lower pair of lugs 19^c and 18, the latter being provided with a stud portion as previously described, upon which is mounted the bell crank 15, these lugs being located on the inner side of 25 the bottom of case 11 as shown in Fig. 9, for example. Similarly case covering 12^a is provided with alining guide lugs 19^d, 19^e, 19^f and 19^g. Slide bar 20 is provided with lug portions 20^e which coact with lugs 19^a 30 and 19^b to limit the withdrawal of the slide bar. Similarly, auxiliary slide bar 21 is provided with similar lugs 21^g coacting, when in the arrangement shown, with lugs 19^d and 19^e, these coacting lugs in the case of the 35 auxiliary slide bar 21 preventing engagement of stud 21^c with the uppermost notch 13^b of the bolt bar 13^a, thereby preventing interference with the unlocking movement of the bolt and bolt bar.

40 Bell crank 15 lies between the slide bar 20 and auxiliary slide bar 21, as shown in Fig. 3, for example. Save for the projecting extremity 21^b and stud 21^c, auxiliary slide bar 21 is similar in construction and size to slide bar 20 and is interchangeable with respect to the guide lugs with said slide bar i. e. auxiliary slide bar 21 may be mounted between lugs 19^a, 19^b, 19^c and 18 while slide bar 20 may be mounted between lugs 19^d, 19^e, 19^f and 19^g, for the purpose to be described 45 hereinafter.

The arrangement of the stud 20^a and slot 21^a is such that the slide bar 20 may be operated to actuate the bell crank 15 to move the bolt 13 out of locking position against the action of the spring 16 without movement of the auxiliary slide bar 21. On the other hand, when the auxiliary slide bar 21, which is provided with a contact face 21^a at 60 its lower end, is actuated, it will engage the stud 20^a and pick up the slide bar 20, thereby actuating the bell crank 15, so that actuation of either the slide bar or auxiliary slide bar 21 will result in actuation of the bell crank 15 to unlock the bolt 13. Release

of the actuating means will result in the slide bars and bell crank being returned to normal position through the actuation of the spring 16. Located at each side of the door 10 are the door plates 25 and 26, the former being located at the outside of the door and the latter at the inside. Suitable handles 25^a and 26^a are provided for opening or closing the door. In Figs. 1 to 3, I have shown a latch-operating mechanism 75 consisting of latch members 28 pivoted at 28^a, one in each of the door plates 25 and 26, these latch members being provided with extremities 28^b projecting through apertures 11^a in the lock casing and lying beneath the contact surfaces 20^b and 21^a of the slide bar and auxiliary slide bar, see Fig. 3. Depression of the latch members 28 will result in actuation of the slide bars, as described above, the latch member located 80 on the outside of the door actuating both slide bars, while the actuation of the inner latch serves to actuate the slide bar 20 only. Located in the upper portion of the lock casing 11 and extending through the door 90 plates is the rotatable shaft 30, capped at the outer end by a cap 31 and having on its inner end an operating handle 32 having the significant extremity 32^a of different configuration than the other extremity 32^b. 95 This shaft is preferably of non-circular cross-section and carries an eccentric driving disc 33 inside the lock casing. Located around and spaced from the shaft is the fixed bushing 34 upon which are rotatably 100 mounted the eccentrically driven discs 35 and 36, (see Fig. 3, for example). Spacing washers 37 are located between the discs, as shown in Fig. 3. The driving disc 33 is provided with a pin 33^a threaded into a suitable hole in the disc and operable to engage a similar pin 35^a similarly carried by a disc 35. This disc has on its opposite face a second pin 35^b, (see Figs. 5 and 14) operable to engage a pin 36^a carried by a disc 36. 110 The discs are provided with enlarged notches 33^b, 35^c, 36^b, respectively, which when in alinement and proper position will accommodate the extremity 21^b of the auxiliary slide bar 21. When in such position, this slide bar may be actuated by the outer 115 latch member 28 to permit movement of the bolt 13. When any of the discs, however, have their notches out of alinement with the extremity 21^c of the auxiliary slide bar, 120 movement of the latter will be prevented and it will be impossible to operate the lock from the exterior of the door.

The driving disc 33 is provided with a second notch 33^d (see Fig. 4). A pair of 125 interacting push bars 40 and 41 are provided having visible ends 40^a and 41^a projecting into the face 12 of the lock casing. These push bars are of conventional construction and are provided with slots 40^b and 41^b, 130

respectively, in which lie the extremities of a lever 42 which is pivotally mounted on a fixed post 43. This construction is such that when the outer end of one push bar is 5 pushed inwardly, the lever 42 will move the other push bar outwardly. The inner extremity 40^c of the push bar 40 is arranged to engage the notch 33^a of the disc 33 when the latter is in position with the notch 33^b 10 alining with the slide bar extremity 21^b, that is, in unlocking position. As is customary in mechanisms of this character, the discs 33, 35, and 36 are actuated through rotation of the shaft 30, the driving disc 33 15 picking up the disc 35 and the latter picking up the disc 36, the operating handle 32 being rotated in the proper manner and in the proper sequence of operations to aline the notches for unlocking of the door from 20 the exterior thereof. When the discs are in unlocking position, the push bar 40 may be moved inwardly until its extremity 40^c engages the notch 33^a when the combination mechanism will be locked in unlocking position, so that it will be impossible to actuate 25 said mechanism.

Similarly, when it is desired to lock the combination mechanism in locked position so that it will be impossible to unlock the same 30 from the exterior of the door, the discs are moved out of unlocking position, after which the operating handle 32 may be rotated until the notch 33^b alone is in unlocking position, the other discs being in locking position 35 when the push rod 40 may be moved inwardly to engage the driving disc. The notch 33^a thereby prevents further manipulation of the driving disc and consequently of the driven discs, which latter being in 40 locked position, prevent unlocking of the door from the outside thereof by preventing movement of the auxiliary slide-bar 21.

To prevent over-travel of the discs 33, 35 and 36, I provide the leaf spring member 45 having portions frictionally bearing upon the discs 33, 35, and 36, and its other extremity being partially bent around the post 46 and into a notch 47^a in the block 47. A spring 48 extends from the post 46 around 50 the guide 49 in which are guided the push bars 40 and 41, and bears at its other extremity against one of the flattened surfaces 42^a of the link 42, the construction being such that whichever of its two extreme 55 positions the lever 42 is in, movement therefrom will be resisted by the spring 48.

In Figs. 7 and 8, I have shown a modification of my invention in which rotatable knobs 50 are substituted for the latch members 28, these knobs each being provided at their inner extremities with rocker arms 51, these rocker arms being seated in the curved portions 11^b with their extremities 51^a in contact with the contact surfaces 20^b and 21^a, 60 so that rotation of the knobs in either di-

rection will result in the actuation of either the slide bar 20 or the auxiliary slide bar 21.

In the arrangement shown, my lock is 70 shown as applied to a door opening inwardly, the slide bar 20 always being toward the inside of the door as is obvious since it is always operated by the inside knob or latch. When it is desired to apply 75 my lock mechanism to a door hinged at the opposite side but opening in the same direction, it is only necessary to remove the bolt bar 13^a and turn it over and also reverse the positions of slidebar 20 and auxiliary slide bar 21 i. e. make the change 80 of each from between one set of guide-lugs to the other as previously described, in which event the other of the notches 13^b will become the operative notch, and the bevel of the bolt 18 will be reversed to correspond to the changed position. This reversibility 85 also permits application of the same mechanism to a door swinging in the opposite direction, but hinged at the same side, in which event it is merely necessary to turn over the bolt-bar 13^a, the relative position of 90 the slide bar and auxiliary slide bar remaining the same.

Located on the outer face of the door plate 95 are the raised radial ribs 55, each rib corresponding to the number in the combination and located about the shaft 30. Each of the ribs 55 is provided with two numerals as shown in Fig. 1, for example, to 100 permit operation of the combination in either direction since location of the locking mechanism on opposite sides of the doors will operate to change the direction of initial rotation of the operating member, in which event one set of numbers may be used while the other may be used when the opposite 105 rotation is required.

Burglars or others seeking to pick or open combination locks endeavor to feel out the combination by holding the slide bar or its equivalent against the discs, while rotating 110 the operating handle 32 which carries the driving disc 33, the idea being that the passage of the notches in the disc past the slide-bar, when in contact with the discs will be perceptible to a skilled operator. To foil 115 any such attempts, I construct my disks eccentrically with the notches 33^b, 35^c and 36^b at the point of least eccentricity or in the portion of lesser eccentricity. Furthermore 120 the pins are so located relative to these notches that notch 36^b of disc 36, which is the first disc to be placed in operating combination, will always be protected by either disc 35 or disc 33 in rotation of two or of all three discs i. e. notch 36^b will underlie 125 portions of greater eccentricity in either disc 33 or 35, or both, so that it will be impossible for its edges to contact with the stud 21^c. Inability to locate this notch will 130 obviously prevent detection of the combina-

4

tion. In addition, I provide a plurality of notches 33^e about the periphery of disc 33 and similarly a plurality of notches 35^e and 36^e, about the peripheries of discs 35 and 36, respectively. These serve to confuse anyone seeking to detect the combination in the manner described by providing a plurality of misleading notches, none of which give any indication of the true unlocking notch.

10 A person using the combination mechanism may set or lock the same from the inside of the door without opening the door by rotating the cap 31 and thereby the driving disc 33 moving the combination mechanism to locked position.

15 To enable a purchaser of my mechanism to ascertain the combination before inserting a lock in the door, I provide sight openings A in the case 11 and case covering plate 12^b in line with the notches 33^b, 35^b and 36^b when the latter are in unlocking position. Also I provide on each side of the case about the center of rotation of shaft 30, a plurality 20 of raised numerals B (see Fig. 11) corresponding in position to the numerals on the ribs 55. To ascertain the combination, the operator will first rotate the operating handle 32 until notch 36^b is in alignment 25 with adjacent opening A, he may then reverse the rotation of the operating handle until notch 35^b in the disc 35 is aligned with notch 36^b and the sight opening A, after which the direction of rotation is again reversed until notch 33^b is aligned with the other two notches at the sight opening A. At this time, the combination mechanism is 30 in unlocking position and if the operator has noted the numerals at the positions of alignment of the respective notches during manipulation of the operating handle, he will then be in possession of the proper combination.

35 It will be obvious that my invention is susceptible of modifications and improvements, and I do not wish to be restricted to the form shown and described except as defined in the appended claims.

I claim:—

40 1. In a device of the class described, a lock bolt and bar, means to move said bolt and bar to unlocking position, said means comprising a plurality of interconnected interchangeable slide bars, actuating means to 45 actuate said slide bars, a bell crank member operatively interposed between said slide bars and said lock bolt and bar, and combination mechanism coacting with one of said slide bars to permit or prevent actuation 50 of said lock bolt and bar.

55 2. In a device of the class described, a reciprocal lock bolt, a bar carrying said bolt, means to move said bar and bolt to unlocking position, said means comprising 60 a slide bar, combination mechanism coact-

ing with said slide bar to permit or prevent unlocking of said bolt, said mechanism comprising a plurality of notched disks, and means to operate said disks, said disks being eccentrically and rotatably mounted.

70

3. In a device of the class described, a reciprocal lock bolt, a bar carrying said bolt, means to move said bar and bolt to unlocking position, said means comprising a slide bar, combination mechanism coacting with said slide bar to permit or prevent unlocking of said bolt, said mechanism comprising a plurality of notched disks, means to operate said disks, said disks being eccentrically and rotatably mounted, and a notch 75 in each of said disks lying in the portion of lesser eccentricity.

75

4. In a device of the class described, a reciprocal lock bolt, a bar carrying said bolt, a slide bar, means operatively interposed between said lock bolt and bar and said slide means, said means comprising a pivotally mounted member having a portion engageable by said slide bar and a portion engaging said bolt bar, the latter being notched 80 on each side to permit inversion for engagement on either side thereof by said member, and combination mechanism coacting with said slide bar to permit or prevent unlocking 85 of said bolt.

90

5. In a device of the class described, a bolt carrying bar, a slide bar on one side of said bolt-carrying bar, an auxiliary slide bar, an operating member located between said slide bar and auxiliary slide bar, said operating member being engageable by one of said slide bars and having a portion engaging said bolt-carrying member, and combination mechanism coacting with one of said slide bars to permit or prevent unlocking 100 of said bolt carrying bar.

95

6. In a device of the class described, a bolt-carrying bar, a slide bar on one side of said bolt-carrying bar, an auxiliary slide bar, an operating member located between 110 said slide bar and said auxiliary slide bar engageable by said slide bar and engaging said bolt-carrying bar, and combination mechanism coacting with one of said slide bars to permit or prevent unlocking of said bolt carrying bar.

115

7. In a device of the class described, a bolt-carrying bar, a slide bar on one side of said bolt-carrying bar, an auxiliary slide bar, an operating member located between 120 said slide bar and auxiliary slide bar engageable by said slide bar and engaging said bolt-carrying bar, said bars being interconnected to permit relative movement of said slide bar, and combination mechanism coacting with one of said slide bars to permit or prevent unlocking of said bolt carrying bar.

125

8. In a device of the class described, a bolt-carrying bar, a slide bar, an auxiliary slide bar, an operating member located be-

130

5 between the latter and said slide bar and engageable by said slide bar, said auxiliary slide bar being provided with a slot and said slide bar having a stud mounted in said slot, and combination mechanism coacting with one of said slide bars to permit or prevent actuation of said bolt carrying bar.

9. In a device of the class described, a locking bolt, a bar carrying said bolt, said 10 bar being provided with a notch in each side thereof, an operating member in engagement with one of said notches, means to actuate said operating member, said means comprising a reciprocable member, means to 15 guide and limit the movement of said reciprocable member, and combination mechanism coacting with said reciprocable member to permit or prevent unlocking of said bolt.

20 10. In a device of the class described, a locking bolt, a bar carrying said bolt, said bar being provided with a notch in each side thereof, an operating member in engagement with one of said notches, means to actuate 25 said operating member, said means comprising a reciprocable member, means to guide and limit the movement of said reciprocable member, said reciprocable member being provided with a stud, and combination mechanism 30 provided with notches alinable to permit movement of said stud in unlocking said bolt member.

11. In a device of the class described, a locking bolt, a bar carrying said bolt, means 35 to reciprocate said bar comprising an auxiliary slide bar, combination mechanism comprising a plurality of rotatable disks, said disks being provided with notches alinable to permit movement of said auxiliary 40 slide bar thereinto, and means to lock said combination mechanism in position to permit such movement of said slide bar.

12. In a device of the class described, a locking bolt, a bar carrying said bolt, means 45 to reciprocate said bar comprising an auxiliary slide bar, combination mechanism comprising a plurality of rotatable disks, said disks being provided with notches alinable to permit movement of said auxiliary slide 50 bar thereinto, and means to lock said combination mechanism in position to permit such movement of said slide bar, said means being operable to lock said combination mechanism in position to prevent movement 55 of said slide bar.

13. In a device of the class described, a locking bolt, a bar carrying said bolt, means 60 to reciprocate said bar comprising an auxiliary slide bar, combination mechanism comprising a plurality of rotatable disks, said disks being provided with notches alinable to permit movement of said auxiliary slide bar thereinto, and means to lock said combination mechanism in position to permit

such movement of said slide bar, said last- 65 named means comprising a reciprocable bar.

14. In a device of the class described, a locking bolt, a bar carrying said bolt, means to reciprocate said bar comprising an auxiliary slide bar, combination mechanism comprising a plurality of rotatable disks, said disks being provided with notches alinable to permit movement of said auxiliary slide bar thereinto, and means to lock said combination mechanism in position to permit 70 such movement of said slide bar, said last-named means comprising a reciprocable bar, one of said disks being provided with a notch other than the locking notch and said reciprocable bar being provided with a portion 75 movable into engagement with said last-named notch to lock said disk and thereby the combination.

15. In a device of the class described, a locking bolt, a bar carrying said bolt, means 80 to reciprocate said bar comprising an auxiliary slide bar, combination mechanism comprising a plurality of rotatable disks, said disks being provided with notches alinable to permit movement of said auxiliary slide 85 bar thereinto, means to lock said combination mechanism in position to permit such movement of said slide bar, and means to move said bar from locking position.

16. In a device of the class described, a locking bolt, a bar carrying said bolt, means 90 to reciprocate said bar comprising an auxiliary slide bar, combination mechanism comprising a plurality of rotatable disks, said disks being provided with notches alinable 95 to permit movement of said auxiliary slide bar thereinto, means to lock said combination mechanism in position to permit such movement of said slide bar, means to move said bar from locking position, said last-named means comprising a second reciprocable bar, and means operatively connecting 100 same with said first-named reciprocable bar.

17. In mechanism of the class described, a casing, a cover therefor, a lock bolt, a bar 110 carrying said bolt and reciprocably mounted in said casing, means to actuate said bolt and bar, said means comprising a slide bar and an auxiliary slide bar, guide lugs located in said casing and on said cover for 115 said slide bars respectively, and lugs carried by said auxiliary slide bar and coacting with said guide lugs to limit the movement in one direction of said auxiliary slide bar.

18. The combination with a door having 120 a lock casing, of a lock bolt therein, a reversible bar carrying said bolt, means to reciprocate said bar comprising a plurality of interchangeable slide bars, one operable for actuating said bolt carrying bar from the 125 outside and the other from the inside of said door, the former having an extension at one end, combination mechanism comprising a

- plurality of rotatable disks, said disks being provided with notches alinable to permit movement of the slide bar having the extension in such wise that the latter may enter 5 said notches to permit of the actuation of said bolt carrying bar, and means whereby the latter may be actuated by means of the other of said slide bars independently of said combination mechanism.
- 10 19. The combination with a door having a lock casing, of a locking bolt therein, a reversible bar carrying said bolt, means to reciprocate said bar comprising a plurality of interchangeable slide bars, one operable for 15 actuating said bolt carrying bar from the outside and the other from the inside of said door, and combination mechanism coacting with the former for permitting or preventing the actuation of said bolt carrying bar.
- 20 20. The combination with a door having a lock casing, of a locking bolt mounted in said casing, a bar carrying said bolt, means to reciprocate said bar comprising a plurality of interconnected interchangeable 25 slide bars, one being operable for actuating said bolt carrying bar from the outside and the other from the inside of said door, the latter being operable independently of the former for effecting such actuation and the 30 former depending upon the interconnection between said bars for its actuation, and combination mechanism to permit or prevent this latter actuation.
21. The combination with a door having a lock casing, of a lock bolt therein, a reversible bar carrying said bolt, means for reciprocating said bar including a plurality of interchangeable slide bars, and combination mechanism coacting with one of said slide bars for permitting or preventing actuation of said first-named bar. 35
22. In a permutation lock, a rotatable driving disk, a rotatable driven disk, coupling means interposed therebetween, and means for operating said driving disk, said 40 disks being eccentrically arranged and each having a notch therein lying in the portion of lesser eccentricity. 45
23. In a permutation lock, a rotatable driving disk, a rotatable driven disk, coupling means interposed therebetween, and means for operating said driving disk, said 50 disks being eccentrically arranged and each having a plurality of notches therein, one notch of each disk being significant and 55 lying in the portion of lesser eccentricity, the others being designed to mislead those attempting to "feel out" the combination. 60
24. In a permutation lock, a plurality of rotatable disks, each having a notch in its periphery, and means for operating said disks, the peripheries of the latter being eccentrically arranged and the notches therein being located in portions of lesser eccentricity. 65

In testimony whereof, I have subscribed my name.

THOMAS E. SHANNON.
